UNITED STATES PATENT OFFICE.

LOUIS A. RIVON, OF DES PLAINES, ILLINOIS.

SWITCH-THROWING DEVICE.

1,233,915.

Specification of Letters Patent. Patented July 17, 1917.

Application filed November 9, 1914. Serial No. 871,065.

To all whom it may concern:

Be it known that I, LOUIS A. RIVON, a citizen of the United States, residing at Des Plaines, in the county of Cook and State of Illinois, have invented certain new and useful Improvements in Switch-Throwing Devices; and I do hereby declare the following to be a full, clear, and exact description of the invention, such as will enable others skilled in the art to which it appertains to make and use the same.

My invention relates to improvements in devices for operating switches particularly for street railways and resides in the provision of simple, effective, and inexpensive means that is to be attached to a street car or like railway vehicle and will operate to move a switch point into the desired position.

Another object of my invention is to provide switch throwing apparatus that is to be controlled by the motorman of a street car or like railway vehicle and is arranged in the forward part of the vehicle so that the motorman or operator of the vehicle may at will move the switch point to the desired position.

Another object of importance is to provide a novel track engaging member that may be moved into and out of operative position and is constructed so as to be rotated to throw the switch point to the desired position.

Another object is to provide a device of the character described that is arranged to be yieldingly extended for engagement with the track or rails and which is provided with antifriction means whereby it freely slidably engages the track and is prevented from becoming deranged.

The above and additional objects are accomplished by such means as are illustrated in the accompanying drawings, described in the following specification and then more particularly pointed out in the claims.

With reference to the drawings, wherein I have illustrated the preferred embodiment of my invention as it is reduced to practice, and throughout the several views of which similar reference numerals designate corresponding parts.

Figure 1 is a longitudinal sectional view taken through a railway car showing my improved switch throwing mechanism in side elevation and attached thereto,

Fig. 2 is a view similar to Fig. 1 showing

the mechanism in out of the way position instead of in operative position, as shown in Fig. 1,

Fig. 3 is a transverse sectional view taken through the railway car showing the operating mechanism in rear elevation,

Fig. 4 is a transverse sectional view taken through the switch.

Fig. 5 is an enlarged detail perspective view of the switch point engaging shoe.

Fig. 6 is a top plan view of the switch point, showing the same in one position and the point engaging shoe in dotted line.

Fig. 7 is a top plan view of the switch point and showing the same in a position opposite to that shown in Fig. 6, and the point engaging shoe in dotted line position.

Fig. 8 is a detail plan view of part of the device.

Referring to the drawings by characters of reference the numeral 1 designates as an entirety a street railway car which has mounted upon the front wall of the front platform 2 thereof a rotary vertical operating shaft 3 that is journaled in suitable bearings 4 carried on the front upright wall. A right angularly extending handle 5 is carried upon the upper end of the rod 3 and provides means for the rotation of the rod.

The rod 3 extends through the platform 2 and its lower end is extended laterally, as at 3', and is received by an opening in a circular head 6' carried by one end of a link 6, the opposite end of the link overlapping and pivotally secured to the upper end of an upwardly extending crank arm 7. The lower end of the crank 7 is connected rigidly to the upper end of a vertical shaft 9 that is rotatably mounted within an opening in the block 8 and is provided with a squared extension on its upper end. The squared extension 10 is designed to extend within an opening of similar nature that is formed in the lower end of the member 7 so as to prevent the member 7 turning relative to the shaft 9.

A bearing ring 11 is secured adjacent to the lower end of the shaft 9 and bears upon the under face of the block 8. Secured upon the lower end of the shaft 9 and extending outwardly at right angles thereto is a wedge shaped switch point engaging shoe 12 that is formed of a rectangular metallic block which is secured at one end and has its free end beveled on opposite sides.

Secured at their lower ends on opposite

sides of the block 8 are upwardly and rearwardly extending supporting arms 13 and 14. Secured upon the forward truck A of the car is an upstanding bracket or arm 15 and connected with the bracket by means of a bifurcated coupling member 16 is the upper end of the arm 13. A pin 17 is inserted through the upper end of the arm 13 and the member 16.

10 The arm 14 is pivotally connected as at 19 at its upper end with the lower end of a slidably mounted pin 20 that is slidably mounted through the body portion of the bracket 15 and has arranged upon its upper end an enlarged head 21. Mounted upon the pin 20 and interposed between the head 21 and bracket 15 is a helical expansion spring 22 that normally holds the pin 20 in up position. This spring 22 is designed to yield 20 upon the motion of the track engaging mechanism toward the tracks so as to prevent derangement of the mechanism.

15 Rotatably mounted upon the arm 13 at a point adjacent to the rear end of the block 8 is a track engaging roller 23 that is arranged to engage the rails when the block 8 is allowed to move into operative position.

20 It will be observed that the block 8 carrying the member 12 is normally supported in spaced relation to the rails and upon releasing of the block 8 and corresponding parts it will rock to coöperative position with the shoe 12 in position to move the switch point as will be later more fully described.

25 As a means for normally holding the switch throwing mechanism in inoperative position, I provide an operating pedal 24 that consists of a relatively straight shank portion 25 and head 26 formed on the upper end thereof. The shank portion 25 is inserted through an elongated opening 27 formed in the platform 2 and is pivoted at a point approximately centrally of its ends 30 as at 28 to a suitable bracket 29 carried upon the under face of the platform 2. A helical retractile spring 30 is secured at one end to an ear 31 carried upon the under face of the platform 2 at a point adjacent to the rod 3 and at its other end to a link member 32. The link member 32 is pivoted centrally of its ends to the lower end of the shank 25 of the pedal 24 and is secured at one end to the lower end of the spring 30.

35 The other end of the member 32 is loosely connected by means of a link, chain or other suitable flexible element 33 to the arm 13. The spring 30 normally holds the pedal 24 in position as shown in Fig. 2 and the mechanism out of engagement with the switch. When the shoe 12 is thus raised from engagement with the trap, the link 6 will be raised bodily upwardly, as shown in Fig. 2, and the lower wall of the opening in the 40 circular head 6 will exert an upward force

on the crank 3' and effect raising of the rod 3 to the position shown in Fig. 2. This upward movement of the shaft 3 admits of the handle 5, at the upper end thereof, being positioned at a point where it can be conveniently grasped by the hand of the operator. Another advantage to be derived from this upward movement of the rod 3 is that should the chain 33 happen to become detached from operative position, when the rod 3 is in raised position, thereby effecting the lowering of the shoe 12, the rod 3 will descend, this downward movement of the rod 3 serving as means by which the operator will be notified of the disconnection of the chain or flexible element 33, and also notifying him of the engagement between the shoe and the track. Also, if the chain should become detached while the shoe is in lowered position, the rod 3 will not be raised upwardly when released, and the operator will then be informed of the continuous engagement of the shoe with the track. In this manner it will be seen that the operator can easily determine when the block is in raised or lowered position. Upon the pressing down of the pedal 24 the block 8 carrying the shoe 12 is allowed to drop into operative position. The chain 33 is mounted upon a roller 33' that is carried upon the under face of the platform 2.

45 Referring to Figs. 4, 6 and 7 wherein there has been illustrated the type of switch necessary to coöperate with my improved switch throwing apparatus, the numeral 34 designates the integrally joined rails at the switch point and 35 designates the ordinarily constructed street railway switch point. The inner faces of the rails 34 are grooved longitudinally or cut away as at 36 to receive the beveled end of the shoe 12 so as to enable the shoe to engage the switch point.

50 In operation, assuming that the device is in out of the way position as illustrated in Fig. 2 in the drawings and it is desirous of throwing the switch point 35 from closed into its other position, the pedal 24 is pushed downwardly allowing the roller 23 carried adjacent to the block 8 to engage upon the rails 34 or adjacent rails of the track and the shoe 12 to extend between the rails 34 and into position for engagement with the switch point 35. Dependent upon the position of the switch the shaft 3 is rotated so as to bring the pointed end of the shoe 12 into either of the grooved faces 36 of the rails 34. By means of the grooved faces 36 which faces extend beyond the point where the free end of the switch point engages one of the rails 34, the shoe 12 is permitted to engage between the switch points and adjacent rail 34 so that upon the grasping of the handles 5 and the rotation of the shaft 3, the switch point 35 will be moved into the desired position. Upon release of pres-

sure upon the pedal 24 the spring 30 will return the mechanism to normal out of the way position as illustrated in Fig. 2 in the drawings. The mechanism in being carried 5 by the truck A is moved in accordance with a curve and the motorman permitted to operate the device.

With reference to the foregoing description and accompanying drawings it will be 10 observed that I have provided a simple switch throwing device that may be easily and readily attached to the forward platform of a street railway car and operated by the motorman to throw a switch point into 15 the desired position without necessitating the motorman getting out of the car. It is only necessary to provide grooved side faces in the rails that are adjacent to the switch points and with this exception the switch 20 structure generally employed need not be changed.

In practice, I have found that the form 25 of my invention, illustrated in the drawings and referred to in the above description, as the preferred embodiment, is the most efficient and practical; yet realizing that the conditions concurrent with the adoption of my device will necessarily vary, I desire to 30 emphasize the fact that various minor changes in details of construction, proportion and arrangement of parts may be resorted to, when required, without sacrificing any of the advantages of my invention, as set forth.

35 What is claimed is:—

1. In a switch throwing mechanism for cars, the combination with a car truck frame and the platform of the car, of an upwardly and forwardly extending arm carried by the 40 said frame, a downwardly and forwardly extending supporting arm located at the forward side of the arm on the truck frame and pivotally connected for vertical swinging movement to the arm on the truck frame, 45 a pin having its shank slidably extending through the arm on the truck frame and having the terminal of its inner end normally extending beyond the inner side of the said arm, a nut threadedly mounted on 50 the inner end of the pin, a spring surrounding the shank of the pin and interposed between the nut and the adjacent side

of the arm on the truck frame, a second vertically movable supporting arm located at the forward side of the arm of the truck 55 frame and disposed adjacent to and in spaced relation with the first-mentioned supporting arm and having one end pivotally connected to the pin, a switch point-engaging shoe rotatably mounted between the supporting arms, an operating pedal, means connecting the operating pedal to one of the supporting arms to effect raising of the arms when the element is in normal position so as to hold the shoe in raised position and to 60 admit of the lowering of the arm when the pedal is operated, means for returning the pedal to normal position after the same has been operated to effect raising of the switch operating shoe, a rotatable shaft, and means 65 for connecting the shaft to the shoe, whereby to admit of the shoe being rotated when in lowered or operative position, for the purpose specified.

2. In a switch throwing device for cars, 75 the combination with a car truck frame and a platform of the car, the said platform having an opening therein, of a pair of vertically swinging supporting arms located at the forward end of the truck frame and 80 each having one end pivoted to the truck frame, a block secured between the supporting arms, a switch point-engaging shoe rotatably supported by the block, an operating pedal disposed above the car platform, a 85 shank carried by the pedal and extending through the opening in the platform and pivoted therein, a link extending transversely of the lower end of the shank, a chain having one end connected to one end 90 of the link and its opposite end connected to one of the supporting arms, and a helical retractile spring located below the platform of the car and in advance of the lower end of the shank and having one end secured to 95 the car platform and its opposite end to the other end of the link, as and for the purpose specified.

In testimony whereof I affix my signature in presence of two witnesses.

LOUIS A. RIVON.
